UNITED STATES PATENT OFFICE.

FRANK P. SIMMEN, OF SAN MATEO, CALIFORNIA, ASSIGNOR TO SUNSET FEATHER COMPANY, OF SAN FRANCISCO, CALIFORNIA.

FEATHER-WASHING MACHINE.

Application filed June 16, 1926. Serial No. 116,405.

My invention relates to improvements in feather washing machines and the like wherein feathers are moved through a vat containing a detergent and agitated therein 5 to obtain a thorough cleansing of the feathers.

The primary object of my invention is to provide an improved machine for washing feathers and the like.

10 Another object is to provide an improved machine provided with improved means for removing the cleaned feathers from a detergent.

15 A further object is to provide an improved device of the character described adapted to facilitate the washing of feathers and to obtain increased efficiency.

20 Another object is to provide an improved machine having means arranged to maintain a constant water level within a vat and to prevent the clogging of the outlet by the feathers being washed.

25 A still further object is to provide an improved feather washing machine of simple and efficient construction adapted for continuous operation.

30 I accomplish these and other objects by means of the improved device disclosed in the drawings forming a part of the present specification wherein like characters of reference are used to designate similar parts throughout said specification and drawings and in which,

35 Fig. 1 is a plan view of my improved feather washing machine; and

Figs. 2 and 3 are longitudinal sectional views taken upon the lines 2—2 and 3—3 respectively of Fig. 1 in the directions indicated.

40 Referring to the drawings the numeral 1 is used to designate in general a vat of any suitable construction adapted to contain water or other suitable detergent. An inlet 2 is connected into one end of the vat 1 and an outlet 3 is connected into the opposite end and upon the opposite side of the vat whereby water or other detergent may be caused to flow through the vat. The vat is divided into inlet and outlet sides by means 45 of longitudinally disposed partitions 4 and 6 connected at a point spaced from the outlet end of the vat by means of a transverse partition 7 to form a passage across the end of the outlet end of the vat. The outlet is connected into the vat at a point below the in-

tended water level of the vat and preferably directly into the bottom of the vat, said outlet being covered by a suitable screen cover 8 and connected to a goose-neck 9 or other suitable connection arranged outside of the vat 1 for maintaining a constant water level within the vat.

45 Agitating mechanism is mounted within the inlet side of the vat 1, said mechanism consisting of a plurality of arms 11 secured upon a longitudinally disposed shaft 12 and provided with blades 13 formed upon their outer ends to operate as propellers for inducing a forward current in the detergent and for propelling feathers or the like through the vat as hereinafter more fully explained. The shaft is provided with a suitable pulley 14 arranged to be driven by a suitable belt 15 from a source of power not shown. The arms 11 are preferably arranged in spiral 75 form along the shaft 12.

50 The side of the vat 1 opposite the agitating mechanism is provided with an inclined bottom 16 extending upwardly from a point adjacent the outlet 3 to a point above the normal water level of the vat. An endless conveyor is mounted adjacent and parallel to the inclined bottom 16, said conveyor consisting of a pair of chains 17 mounted over suitable sprockets 18 mounted upon shafts 19, the upper one of which is arranged to be driven through a suitable worm gear 21 or other suitable driving mechanism connected thereto in any convenient manner. A plurality of combs 22 are mounted upon the conveyor and arranged to dip into the detergent above the submerged portion of the bottom 16 and to be moved upwardly past the outwardly extending portion of said bottom.

55 In operation water or a suitable detergent 95 solution is circulated through the vat 1, said water or solution being introduced through the inlet 1, preferably as a constant flow, and allowed to overflow through the outlet 3 and goose-neck 9 to maintain a normal 100 water level within the vat at a point slightly below the upper end of the inclined bottom 16. Feathers or other like material to be washed, are introduced into the inlet side of the vat 1 through a suitable hopper 23 arranged above the water inlet 2. The feathers are agitated within the water or solution and thoroughly washed by means of the agitating arms 11 which are constantly rotated within the solution, the blade portions 105 110

13 of said arms creating a current combining with the natural flow of water or solution and operating to propel the feathers through the vat.

5 As the feathers reach a point above the outlet 3 they are engaged by the combs 22 which are arranged to dip into the water or solution adjacent said outlet and to move through the water along a path closely parallel to the bottom 16. The feathers, of course, float upon the surface of the water and as the combs are moved through the water the feathers are carried along the surface of the water until the outwardly extending portion of the bottom 16 is reached. Here the combs 22 operate to rake the feathers from the surface of the water and onto the sloping bottom 16, the feathers being thus removed from the water without 15 exerting any direct lifting effort and without causing the feathers to cling to the combs. The further movement of the combs operates to rake the feathers along the outwardly extending portion of the sloping bottom 16, said feathers being moved outwardly over the outer end of said bottom and received in a suitable hopper 24 arranged adjacent thereto.

30 The machine may be kept in continuous operation, feathers being introduced at a rate regulated to obtain an efficient operation. The dirt and refuse washed from the feathers is constantly carried away by the flow of the detergent through the vat. Any 35 heavy or bulky refuse introduced with the feathers collects in the bottom of the vat. To facilitate the removal of such refuse from the vat, a drain cock 26 is mounted in connection with the outlet 3 whereby the 40 vat may be drained periodically to permit the removal of such refuse.

While I have illustrated and described what I now consider to be the preferred

embodiment of my invention, the specific details of construction may of course be modified in numerous ways without departing from the spirit of my invention. I therefore do not wish to restrict myself to the specific construction disclosed, but desire to avail myself of all modifications which may fall within the scope of the appended claim.

Having thus described my invention what I claim as new and desire to secure by Letters Patent is:

55 A feather washing machine comprising a vat provided with an inlet and an outlet connected into opposite ends of the vat for circulating a detergent solution therethrough; a longitudinally disposed partition in the vat extending from the inlet end to a point spaced from the outlet end of the vat, the inlet and outlet being arranged upon opposite sides of said partition; agitating means mounted within the inlet side of the vat for agitating feathers introduced therewith and for propelling said feathers through the detergent; an inclined bottom mounted within the outlet side of the vat and arranged to slope upwardly to a point above the water level of the vat; an endless conveyor mounted adjacent the sloping bottom; combs mounted upon the conveyor and arranged to dip into the detergent above the submerged portion of the bottom to move the feathers from the solution onto the upwardly extending portion of said bottom; and means arranged outside of the vat and connected to the outlet for maintaining a constant water level within the vat said outlet being arranged below the water level to prevent the clogging thereof by the feathers.

75 In witness whereof, I hereunto set my signature.

FRANK P. SIMMEN.
